(57) **ABSTRACT**

A container mounting structure includes a container and a container mounting portion. The container extends in one direction and contains powder. The container is mounted to the container mounting portion by rotating the container disposed at a temporarily placed position in a circumferential direction of the container. In a state in which the container is mounted to the container mounting portion, the container mounting structure has contact sections where the container is in contact with the container mounting portion in a radial direction of the container. Each of the contact sections is disposed at corresponding one of at least three different positions in the circumferential direction. The container is in contact with the container mounting portion from inside in the radial direction at one subset of the contact sections and from outside in the radial direction at another subset of the contact sections.

**CROSS-REFERENCE TO RELATED
APPLICATIONS**

This application is based on and claims priority under 35 USC 119 from Japanese Patent Application No. 2018-236594 filed Dec. 18, 2018.

BACKGROUND

(i) Technical Field

The present disclosure relates a container mounting structure, an image forming unit, and an image forming apparatus.

(ii) Related Art

Japanese Unexamined Patent Application Publication No. 2006-208574 describes a container that includes a bottle body and a cap. The bottle body has a cylindrical shape and includes a helical transport section. When rotated, the transport section transports toner contained therein toward a mouth portion. The cap is mounted to the mouth portion of the bottle body, provided with a replenishment port and a gripping portion at its circumferential surface, and rotatable relative to the bottle body.

SUMMARY

A container extends in one direction and contains powder. When this container is disposed at a temporarily placed position in a container mounting portion and the container disposed at the temporarily placed position is rotated to one side in the container circumferential direction, the container is mounted to the container mounting portion.

In a mounting structure for this container, the container is moved toward the container mounting portion in the intersecting direction so as to be disposed at the temporarily placed position. Then, by rotating the container disposed at the temporarily placed position in the container circumferential direction, the container is mounted to the container mounting portion.

In such a structure, in order to position the container relative to the container mounting portion in a container radial direction, the container and the container mounting portion are brought into contact with each other in three contact sections disposed at different positions in the container circumferential direction. In the related art, the container is in contact with the container mounting portion from inside in the container radial direction at all the contact sections.

Aspects of non-limiting embodiments of the present disclosure relate to improvement of accuracy in positioning a container relative to a container mounting portion compared to the case where the container is in contact with the container mounting portion from inside in the container radial direction at all contact sections in a structure in which the container is mounted to the container mounting portion when the container disposed at a temporarily placed position is rotated.

Aspects of certain non-limiting embodiments of the present disclosure overcome the above disadvantages and/or other disadvantages not described above. However, aspects

2

of the non-limiting embodiments are not required to overcome the disadvantages described above, and aspects of the non-limiting embodiments of the present disclosure may not overcome any of the disadvantages described above.

According to an aspect of the present disclosure, there is provided a container mounting structure including a container and a container mounting portion. The container extends in one direction and contains powder. The container is mounted to the container mounting portion by rotating the container disposed at a temporarily placed position in a circumferential direction of the container. In a state in which the container is mounted to the container mounting portion, the container mounting structure has contact sections where the container is in contact with the container mounting portion in a radial direction of the container. Each of the contact sections is disposed at corresponding one of at least three different positions in the circumferential direction. The container is in contact with the container mounting portion from inside in the radial direction at one subset of the contact sections and from outside in the radial direction at another subset of the contact sections.

BRIEF DESCRIPTION OF THE DRAWINGS

Exemplary embodiment of the present disclosure will be described in detail based on the following figures, wherein:

FIG. 1 schematically illustrates the structure of an image forming apparatus according to an exemplary embodiment of the present disclosure;

FIG. 2 schematically illustrates the structure of the image forming apparatus according to the exemplary embodiment of the present disclosure;

FIG. 3 schematically illustrates the structure of an image forming unit according to the exemplary embodiment of the present disclosure;

FIG. 4 is a perspective view of a container mounting structure according to the exemplary embodiment of the present disclosure illustrating a state in which a container is disposed at a mounted position;

FIG. 5 is a perspective view of the container mounting structure according to the exemplary embodiment of the present disclosure illustrating a state in which the container is disposed at a temporarily placed position;

FIG. 6 is a perspective view of the container mounting structure according to the exemplary embodiment of the present disclosure illustrating a state in which the container is removed from a container mounting portion;

FIG. 7 is a perspective view of the container mounting portion of the container mounting structure according to the exemplary embodiment of the present disclosure;

FIG. 8 is an enlarged perspective view of the container used for the container mounting structure according to the exemplary embodiment of the present disclosure;

FIG. 9 is an enlarged perspective view of the container used for the container mounting structure according to the exemplary embodiment of the present disclosure;

FIG. 10 is an enlarged perspective view of the container used for the container mounting structure according to the exemplary embodiment of the present disclosure;

FIG. 11 is an enlarged perspective view of the container used for the container mounting structure according to the exemplary embodiment of the present disclosure;

FIG. 12 is a perspective view of the container used for the container mounting structure according to the exemplary embodiment of the present disclosure;

FIG. 13 is a perspective view of the container used for the container mounting structure according to the exemplary embodiment of the present disclosure;

FIGS. 14A and 14B are perspective views of an opening/closing member mounted to the container used for the container mounting structure according to the exemplary embodiment of the present disclosure;

FIG. 15 is an enlarged perspective view of a container mounting portion used for the container mounting structure according to the exemplary embodiment of the present disclosure;

FIG. 16 is an enlarged perspective view of the container mounting portion used for the container mounting structure according to the exemplary embodiment of the present disclosure;

FIG. 17 is an enlarged perspective view of the container mounting portion used for the container mounting structure according to the exemplary embodiment of the present disclosure;

FIG. 18 is a sectional view illustrating the state in which the container is disposed at the temporarily placed position in the container mounting structure according to the exemplary embodiment of the present disclosure;

FIG. 19 is a sectional view illustrating the state in which the container is disposed at the temporarily placed position in the container mounting structure according to the exemplary embodiment of the present disclosure;

FIG. 20 is a sectional view illustrating the state in which the container is disposed at the temporarily placed position in the container mounting structure according to the exemplary embodiment of the present disclosure;

FIG. 21 is a sectional view illustrating the state in which the container is disposed at the temporarily placed position in the container mounting structure according to the exemplary embodiment of the present disclosure;

FIG. 22 is a sectional view illustrating the state in which the container is disposed at the temporarily placed position in the container mounting structure according to the exemplary embodiment of the present disclosure;

FIG. 23 is a sectional view illustrating the state in which the container is disposed at the mounted position in the container mounting structure according to the exemplary embodiment of the present disclosure;

FIG. 24 is a sectional view illustrating the state in which the container is disposed at the mounted position in the container mounting structure according to the exemplary embodiment of the present disclosure;

FIG. 25 is a sectional view illustrating the state in which the container is disposed at the mounted position in the container mounting structure according to the exemplary embodiment of the present disclosure;

FIGS. 26A and 26B are sectional views respectively illustrating the state in which the container is disposed at the temporarily placed position and the state in which the container is disposed at the mounted position in the container mounting structure according to the exemplary embodiment of the present disclosure;

FIG. 27 is an enlarged perspective view of a container used for a container mounting structure according to a comparative embodiment compared to the exemplary embodiment of the present disclosure;

FIG. 28 is a sectional view of the container mounting structure according to the comparative embodiment compared to the exemplary embodiment of the present disclosure illustrating a state in which the container is disposed at the temporarily placed position;

FIG. 29 is a sectional view of the container mounting structure according to the comparative embodiment compared to the exemplary embodiment of the present disclosure illustrating a state in which the container is disposed at the mounted position; and

FIG. 30 is a sectional view of the container mounting structure according to the comparative embodiment compared to the exemplary embodiment of the present disclosure illustrating the state in which the container is disposed at the mounted position.

DETAILED DESCRIPTION

Examples of a container mounting structure, an image forming unit, and an image forming apparatus according to an exemplary embodiment of the present disclosure are described with reference to FIGS. 1 to 30. An arrow H illustrated in the drawings indicates an apparatus up-down direction (vertical direction), an arrow W illustrated in the drawing indicates an apparatus width direction (horizontal direction), and an arrow D illustrated in the drawings indicates an apparatus depth direction (horizontal direction). Overall Structure of the Image Forming Apparatus

As illustrated in FIG. 1, an image forming apparatus 10 according to the present exemplary embodiment includes a containing section 14, a transport section 16, and an image forming section 20 disposed in this order from a lower side to an upper side in the up-down direction (arrow H direction). The containing section 14 contains sheet media P. The sheet media P each serve as a recording medium. The transport section 16 transports the sheet media P contained in the containing section 14. The image forming section 20 forms images on the sheet media P transported by the transport section 16 from the containing section 14. The image forming apparatus 10 also includes an apparatus body 12 in which various components of the image forming apparatus 10 are disposed.

The Containing Section 14

The containing section 14 includes a containing member 26 able to be drawn forward in the apparatus depth direction from the apparatus body 12 of the image forming apparatus 10. The sheet media P are loaded in the containing member 26. The containing section 14 also includes a feed roller 30 that feeds each of the sheet media P loaded in the containing member 26 to a transport path 28 included in the transport section 16.

The Transport Section 16

The transport section 16 includes transport rollers 32 and transport rollers 34. The transport rollers 32 transport the sheet medium P along the predetermined transport path 28. The transport rollers 34 transport the sheet medium P along an inversion path 54 through which the sheet medium P passes so as to be inverted.

The Apparatus Body 12

The apparatus body 12 includes an openable door 56. The door 56 allows, when opened, the inside of the apparatus body 12 to be exposed to the outside of the apparatus body 12. The door 56 has an L shape when seen in the apparatus depth direction and includes a top plate 56a and a side plate 56b. The top plate 56a covers an image forming unit 18 from above. The side plate 56b covers the image forming unit 18 from one side (left side in FIG. 1) in the apparatus width direction. The door 56 also includes a rotation shaft 56c that is disposed at a lower portion of the side plate 56b and extends in the apparatus depth direction.

With the above-described structure, when the door 56 is rotated about the rotation shaft 56c, the door is movable to

a closed position (see FIG. 1) and an open position (see FIG. 2). When the door 56 is at the closed position, the inside of the apparatus body 12 is blocked. When the door 56 is at the open position, the inside of the apparatus body 12 is exposed. An angle by which the door 56 is rotated is regulated by a stopper (not illustrated).

The Image Forming Section 20

The image forming section 20 includes the image forming unit 18, an image holding body 36, a charging roller 38, and a light exposure device 42. The image forming unit 18 forms a black image. The charging roller 38 charges the surface of the image holding body 36. The light exposure device 42 radiates exposure light to the charged image holding body 36.

The image forming unit 18 includes a developing device 40, a container 60, and so forth. The light exposure device 42 causes the charged image holding body 36 to be exposed to light so as to form an electrostatic latent image. This electrostatic latent image is developed by the developing device 40 with toner as powder so as to be visible as a toner image. The container 60 supplies the toner as the powder to the developing device 40. The developing device 40 is an example of a developing section. The details of the image forming unit 18 will be described later.

The image forming section 20 further includes a transfer roller 44 and a fixing device 50. The transfer roller 44 transfers the toner image formed on the image holding body 36 onto the sheet medium P at a transfer position T. The fixing device 50 applies heat and pressure to the sheet medium P so as to fix the toner image to the sheet medium P.

In the above-described structure, the image forming unit 18 is removable from and mountable to the apparatus body 12 when the door 56 is disposed at the open position (see FIG. 2).

Operations of the Image Forming Apparatus

The image forming apparatus 10 forms an image as follows.

First, the charging roller 38 to which a voltage has been applied is brought into contact with the surface of the image holding body 36 so as to uniformly negatively charge the surface of the image holding body 36 to a predetermined potential. Next, the light exposure device 42, based on data input from the outside, radiates the exposure light to the surface of the charged image holding body 36 so as to form an electrostatic latent image.

Thus, the electrostatic latent image corresponding to the data is formed on the surface of the image holding body 36. Furthermore, the developing device 40 included in the image forming unit 18 develops the electrostatic latent image with the toner as the powder so as to obtain a visible toner image.

The sheet medium P having been fed from the containing member 26 to the transport path 28 by the feed roller 30 is fed to the transfer position T through the transport path 28. At the transfer position T, the sheet medium P is transported while being pinched between the image holding body 36 and the transfer roller 44, thereby the toner image on the surface of the image holding body 36 is transferred onto the sheet medium P.

The toner image having been transferred onto the sheet medium P is fixed to the sheet medium P by the fixing device 50. The sheet medium P to which the toner image has been

fixed is output to the outside of the apparatus body 12 by a subset of the transport rollers 32.

Structures

Next, the image forming unit 18 is described.

As illustrated in FIGS. 3, 4, and 6, the image forming unit 18 includes the developing device 40, the container 60, and a unit body 80. The container 60 contains the toner as the powder to be supplied to the developing device 40. The unit body 80 allows various members to be mounted therein. The unit body 80 has a container mounting portion 82 to which the container 60 is mounted. A container mounting structure 52 includes the container 60 and the container mounting portion 82.

The container 60 is temporarily placed in the container mounting portion 82 by moving the container 60 downward from above relative to the container mounting portion 82 (in a direction intersecting the apparatus depth direction; see FIG. 5). Thus, the container 60 is disposed at a predetermined temporarily placed position ("temporarily placed position" hereinafter). Furthermore, the container 60 is mounted to the container mounting portion 82 by rotating the container 60 disposed at the temporarily placed position to one side in the circumferential direction of the container 60 (counterclockwise side, that is, an arrow F01 side in, for example, FIG. 4 when seen from the front in the apparatus depth direction; see FIG. 4). In this state, the container 60 is disposed at a mounted position.

The container 60 is removable and mountable when the image forming unit 18 is mounted to the apparatus body 12 and also when the image forming unit 18 is removed from the apparatus body 12.

The Developing Device 40

As illustrated in FIG. 3, the developing device 40 includes a developing roller 46, a supply auger 48a, and an agitating auger 48b. The developing roller 46 passes the toner as the powder to the electrostatic latent image formed on the image holding body 36. The supply auger 48a supplies the toner to the developing roller 46. The agitating auger 48b agitates the toner.

The developing roller 46 faces the image holding body 36 in the apparatus width direction. The supply auger 48a is disposed at a position on the opposite side to the image holding body 36 with the developing roller 46 interposed therebetween in the apparatus width direction and below the developing roller 46. The agitating auger 48b is disposed at a position on the opposite side to the developing roller 46 with the supply auger 48a interposed therebetween in the apparatus width direction and above the supply auger 48a. The Container 60

As illustrated in FIG. 3, the container 60 is disposed above the agitating auger 48b included in the developing device 40. As illustrated in FIGS. 12 and 13, the container 60 extends in the apparatus depth direction (serving as an example of one direction). The container 60 includes a container portion

62 and a lid portion 68. The container portion 62 contains the toner therein. The lid portion 68 is mounted at a front (serving as an example of one side) part of the container portion 62 in the apparatus depth direction. The container portion 62 and the lid portion 68 are parts of a container body 58. FIGS. 12 and 13 illustrate the container 60 oriented for the disposition at the temporarily placed position in the container mounting portion 82.

The lid portion 68 has an opening 72c (see FIGS. 8 and 9) through which the toner is discharged to the outside. The container 60 includes an opening/closing member 78 (see FIGS. 9 and 10) that allows the opening 72c to be exposed and closes the opening 72c. FIGS. 8 and 10 illustrate the

container 60 oriented for disposition at the temporarily placed position in the container mounting portion 82. FIG. 9 illustrates the container 60 oriented for disposition at the mounted position in the container mounting portion 82.

The Container Portion 62

The container portion 62 is integrally formed of a resin material. As illustrated in FIGS. 12 and 13, the container portion 62 has a bottle shape extending in the apparatus depth direction and has a mouth portion 62a at a front end portion thereof in the apparatus depth direction. A section perpendicular to the longitudinal direction of the container portion 62 has a circular shape centered at a central line CL01 of the container 60. The container portion 62 has a helical groove 64 in an outer circumferential surface 62b thereof. The groove 64 forms a helical projection 66 in an inner circumferential surface 62c of the container portion 62. The projection 66 projects from the inner circumferential surface 62c inward in the container portion 62.

With the above-described structure, the toner contained in the container portion 62 is moved from a rear part to a front part in the apparatus depth direction due to the helical projection 66 by rotating the container portion 62 in the circumferential direction of the container portion 62 ("container circumferential direction" hereinafter). That is, the toner contained in the container portion 62 is moved toward the lid portion 68.

The Lid Portion 68

The lid portion 68 is integrally formed of a resin material. As illustrated in FIGS. 12 and 13, the lid portion 68 is mounted at the front part of the container portion 62 in the apparatus depth direction such that the lid portion 68 is able to be movable relative to the container portion 62 in the container circumferential direction. The lid portion 68 includes a first cylindrical portion 70, a second cylindrical portion 72, a gripping portion 74, and a distal end portion 76. The axis of the first cylindrical portion 70 having a cylindrical shape is coincident with the central line CL01. The axis of the second cylindrical portion 72 having a cylindrical shape is coincident with the central line CL01. The gripping portion 74 is gripped by a user. The first cylindrical portion 70, the second cylindrical portion 72, and the distal end portion 76 are arranged in the apparatus depth direction. The gripping portion 74 projects from the first cylindrical portion 70 and the second cylindrical portion 72.

The First Cylindrical Portion 70 and the Second Cylindrical Portion 72

As illustrated in FIGS. 8 and 10, the first cylindrical portion 70 and the second cylindrical portion 72 are arranged in this order from the rear part to the front part in the apparatus depth direction. The first cylindrical portion 70 has a larger diameter than that of the second cylindrical portion 72. The front part of the container portion 62 in the apparatus depth direction is inserted into the first cylindrical portion 70.

As illustrated in FIG. 8, a step portion 72b projecting from an outer circumferential surface 72a of the second cylindrical portion 72 is formed on part of the outer circumferential surface 72a facing downward. The step portion 72b extends in the apparatus depth direction when seen in the radial direction of the container 60 ("container radial direction" hereinafter), and a front part of the step portion 72b in the apparatus depth direction extends to another side in the container circumferential direction (toward an arrow F02 side in, for example, FIG. 8). Furthermore, the step portion 72b has an arcuate shape centered at the central line CL01 when seen in the apparatus depth direction.

The step portion 72b has the opening 72c having a rectangular shape extending in the apparatus depth direction. The inside of the container 60 is to be exposed to the outside through the opening 72c. The opening 72c faces downward when the container 60 is oriented for the disposition at the temporarily placed position.

The second cylindrical portion 72 also has an extended surface 72d formed by extending part of the outer circumferential surface 72a toward the front in the apparatus depth direction. The extended surface 72d is disposed, in the container circumferential direction, at a position on the other side relative to the step portion 72b and on the one side relative to the gripping portion 74, which will be described later.

Furthermore, the second cylindrical portion 72 has a pair of guide grooves 90, 92 in the outer circumferential surface 72a thereof. The opening/closing member 78 (see FIG. 9) that allows the opening 72c to be exposed and closes the opening 72c is guided through the guide grooves 90, 92 in the container circumferential direction. The first cylindrical portion 70 has a guide projection 94 through which the opening/closing member 78 is guided in the container circumferential direction.

The guide groove 90 extends in the container circumferential direction in part of the step portion 72b near the first cylindrical portion 70 and has a U shape in section which is open at the rear in the apparatus depth direction (opposite to the opening 72c). The guide groove 90 is divided into a guide groove 90a and a guide groove 90b kept separated from each other in the container circumferential direction. The guide groove 90a and the guide groove 90b are arranged in this order from the other side to the one side (the arrow F01 side in, for example, FIG. 8) in the container circumferential direction.

The guide projection 94 projects from an end surface 70a of the first cylindrical portion 70 facing the second cylindrical portion 72 toward the front in the apparatus depth direction. The guide projection 94, the guide groove 90a, and the guide groove 90b are arranged in this order from the other side to the one side in the container circumferential direction.

The guide groove 92 extends in the container circumferential direction in a portion of the step portion 72b opposite to the first cylindrical portion 70 and has a U shape in section which is open at the front in the apparatus depth direction (opposite to the opening 72c). The guide groove 92 extends to the other side in the container circumferential direction relative to a range where the guide groove 90a and the guide groove 90b are formed in the container circumferential direction.

Furthermore, a surface that defines the guide groove 92 and faces inward in the container radial direction is a contact surface 106 that is brought into contact with the container mounting portion 82 so as to position the container 60 relative to the container mounting portion 82 (the details will be described later). This contact surface 106 has an arcuate shape centered at the central line CL01 when seen in the apparatus depth direction.

With the above-described structure, in the apparatus depth direction, the guide projection 94, the guide groove 90a, and the guide groove 90b are in contact with a rear part of the opening/closing member 78 and the guide groove 92 is in contact with a front part of the opening/closing member 78. The opening/closing member 78 is guided in the container circumferential direction through the guide grooves 90, 92 and the guide projection 94 (see FIGS. 9 and 10).

Furthermore, as illustrated in FIG. 8, the second cylindrical portion 72 has regulating projections 96 at the outer circumferential surface 72a thereof. The regulating projections 96 regulate the position of the lid portion 68 of the container 60 disposed at the temporarily placed position. Two regulating projections 96 are provided. The regulating projections 96 project from a portion of the step portion 72b on the other side in the container circumferential direction to the other side in the container circumferential direction.

With this structure, in the state in which the container 60 is disposed at the temporarily placed position, the regulating projections 96 are in contact with a suppressing plate 150, which will be described later, formed in the opening/closing member 78, thereby regulating rotation of the lid portion 68 to the other side in the container circumferential direction (see FIG. 19).

Furthermore, as illustrated in FIG. 8, the second cylindrical portion 72 has a limiting portion 98 at the outer circumferential surface 72a thereof. The limiting portion 98 limits a movement of the opening/closing member 78 relative to the lid portion 68. The limiting portion 98 is formed in a portion of the step portion 72b extending to the other side in the container circumferential direction. The limiting portion 98 has a cantilever shape having a free end at a portion thereof on the other side in the container circumferential direction. A recess 98a open toward the outside in the container radial direction is formed near the free end in the limiting portion 98.

With this structure, the recess 98a is engaged with a protrusion 140, which will be described later, formed in the opening/closing member 78, thereby limiting the movement of the opening/closing member 78 (see a two-dot chain line illustrated in FIG. 21). In other words, the recess 98a is engaged with the protrusion 140, which will be described later, formed in the opening/closing member 78, thereby relative movements of the lid portion 68 and the opening/closing member 78 to each other are limited.

The Gripping Portion 74

As illustrated in FIGS. 8 and 10, the gripping portion 74 has a plate shape the plate surface of which faces in the container circumferential direction. The gripping portion 74 projects outward in the container radial direction from the first cylindrical portion 70 and the second cylindrical portion 72. Specifically, when seen in the apparatus depth direction, the gripping portion 74 projects outward in the container radial direction from the opposite side to the opening 72c with the first cylindrical portion 70 and the second cylindrical portion 72 interposed therebetween.

The Distal End Portion 76

As illustrated in FIGS. 8, 9, 10, and 11, the distal end portion 76 is formed in front of the second cylindrical portion 72 (opposite to the first cylindrical portion 70) in the apparatus depth direction. The distal end portion 76 has a frame shape which is open at the front in the apparatus depth direction. FIG. 11 illustrates the container 60 oriented for the disposition at the temporarily placed position in the container mounting portion 82.

Contact surfaces 102, 104 that are brought into contact with the container mounting portion 82 are formed in an outer circumferential surface 76a of the distal end portion 76 so as to position the container 60 relative to the container mounting portion 82. Furthermore, a guide surface 108 and a marked surface 112 are formed in the outer circumferential surface 76a. The guide surface 108 is brought into contact with the container mounting portion 82 so as to dispose the container 60 at the temporarily placed position in the container mounting portion 82 when the container 60 is moved

downward from above the container mounting portion 82. The marked surface 112 allows the user to understand the position of the container 60 in the container circumferential direction.

As illustrated in FIG. 8, the contact surface 102 is disposed, in the container circumferential direction, at a position on the other side relative to the step portion 72b and on the one side relative to the gripping portion 74. Specifically, in the outer circumferential surface 76a of the distal end portion 76, an arcuate surface 116 is formed at a position substantially the same as that of the step portion 72b in the container circumferential direction. The diameter of the arcuate surface 116 is smaller than that of the outer circumferential surface 72a of the second cylindrical portion 72. Furthermore, the contact surface 102 and an auxiliary surface 118 are formed on the other side relative to the arcuate surface 116 with a step interposed therebetween in the container circumferential direction. The diameters of the contact surface 102 and the auxiliary surface 118 are larger than that of the arcuate surface 116. The contact surface 102 and the auxiliary surface 118 are arranged in this order from the one side to the other side in the container circumferential direction.

The contact surface 102 faces outward in the container radial direction and has a smaller diameter than that of the outer circumferential surface 72a of the second cylindrical portion 72. This contact surface 102 has an arcuate shape centered at the central line CL01 when seen in the apparatus depth direction. Furthermore, the diameter of the auxiliary surface 118 is smaller than that of the contact surface 102.

As illustrated in FIG. 9, the contact surface 104 is disposed, in the container circumferential direction, at a position on the one side relative to the step portion 72b and on the other side relative to the gripping portion 74. Specifically, the contact surface 104 is formed on the one side relative to the arcuate surface 116 with a step interposed therebetween in the container circumferential direction. The diameter of the contact surface 104 is larger than that of the arcuate surface 116.

The contact surface 104 faces outward in the container radial direction and has a smaller diameter than that of the outer circumferential surface 72a of the second cylindrical portion 72. This contact surface 104 has an arcuate shape centered at the central line CL01 when seen in the apparatus depth direction.

Furthermore, as illustrated in FIG. 18, when seen in the apparatus depth direction, a line segment L01 connects the central line CL01 and a central portion of the contact surface 102 to each other in the container circumferential direction, and a line segment L02 connects the central line CL01 and a central portion of the contact surface 104 to each other in the container circumferential direction. In this case, an angle R01 formed between the line segment L01 and the line segment L02 is smaller than 180 degrees. FIG. 18 illustrates the container 60 disposed at the temporarily placed position in the container mounting portion 82.

As illustrated in FIGS. 9 and 11, the guide surface 108 is disposed, in the container circumferential direction, at a position on the one side relative to the step portion 72b and on the other side relative to the gripping portion 74. Specifically, the guide surface 108 is formed on the one side relative to the contact surface 104 in the container circumferential direction and adjacent to the contact surface 104. The guide surface 108 has a flat shape and, in the state in which the container 60 is disposed at the temporarily placed position, faces the other side in the apparatus width direction and extends in the up-down direction.

11

As illustrated in FIG. 11, the marked surface 112 is disposed, in the container circumferential direction, at a position on the one side relative to the guide surface 108 and on the other side relative to the auxiliary surface 118. Specifically, the marked surface 112 is formed on the other side relative to the auxiliary surface 118 with a step interposed therebetween in the container circumferential direction. The diameter of the marked surface 112 is larger than that of the outer circumferential surface 72a of the second cylindrical portion 72.

Furthermore, the marked surface 112 has an arcuate shape centered at the central line CL01 when seen in the apparatus depth direction. Furthermore, a triangular mark 112a the vertex of which points toward the front in the apparatus depth direction is formed on the marked surface 112.

The Opening/Closing Member 78

The opening/closing member 78 is mounted to the lid portion 68 such that the opening/closing member 78 is movable relative to the lid portion 68 in the container circumferential direction. The opening/closing member 78 is moved relative to the lid portion 68 to an open position (see FIG. 9) where the opening/closing member 78 allows the opening 72c formed in the lid portion 68 to be exposed and a closed position (see FIG. 10) where the opening/closing member 78 closes the opening 72c.

As illustrated in FIG. 10, the opening/closing member 78 is mounted to the outer circumferential surface 72a of the second cylindrical portion 72 of the lid portion 68 and has a rectangular shape extending in the container circumferential direction when seen from the outside in the container radial direction.

The opening/closing member 78 has a curved plate 120 and a side plate 130. The curved plate 120 extends along the outer circumferential surface 72a while being kept separated, in the container radial direction, from the outer circumferential surface 72a. The side plate 130 projects from an edge portion of the curved plate 120 near the first cylindrical portion 70 toward the outer circumferential surface 72a and extends in the container circumferential direction. Furthermore, the opening/closing member 78 has a side plate 134 and a side plate 138. The side plate 134 projects from an edge portion of the curved plate 120 opposite to the first cylindrical portion 70 toward the outer circumferential surface 72a and extends in the container circumferential direction. The side plate 138 projects from an edge portion of the curved plate 120 on the other side in the container circumferential direction toward the outer circumferential surface 72a and extends in the apparatus depth direction. The side plates 130, 134, 138 in combination form a U shape when seen from the outside in the container radial direction. The side plate 138 is an example of an edge portion.

The Side Plate 130

As illustrated in FIG. 14B, a projecting portion 130a is formed at a distal end portion of the side plate 130. The projecting portion 130a projects toward the side plate 134 and extends in the container circumferential direction. This projecting portion 130a is inserted into the guide grooves 90a, 90b illustrated in FIG. 8. Furthermore, an outer side surface 130b of the side plate 130 is brought into contact with the guide projection 94 illustrated in FIG. 8.

The Side Plate 134

As illustrated in FIG. 14B, a projecting portion 134a is formed at a distal end portion of the side plate 134. The projecting portion 134a projects toward the side plate 130 and extends in the container circumferential direction. This projecting portion 134a is inserted into the guide groove 92 illustrated in FIG. 8.

12

With this structure, the opening/closing member 78 having been mounted to the lid portion 68 is moved in the container circumferential direction relative to the lid portion 68 along the outer circumferential surface 72a of the second cylindrical portion 72.

The Curved Plate 120

As illustrated in FIG. 14B, the protrusion 140 and a through hole 142 are formed in an inner circumferential surface 120a of the curved plate 120. The protrusion 140 is engaged with the recess 98a of the limiting portion 98 formed in the second cylindrical portion 72 (see FIG. 8). The through hole 142 penetrates through the curved plate 120. Furthermore, a rib 144 and a projecting portion 146 are formed in the curved plate 120. The plate-shaped rib 144 projects from the inner circumferential surface 120a. The projecting portion 146 projects from the inner circumferential surface 120a and has the suppressing plate 150 that suppresses a movement of the toner as the powder.

Furthermore, as illustrated in FIG. 14A, a pair of regulating projections 152 is formed on an outer circumferential surface 120b of the curved plate 120 so as to project from the outer circumferential surface 120b. Each of the regulating projections 152 is an example of an engagement portion.

Furthermore, a portion of the inner circumferential surface 120a of the curved plate 120 facing the opening 72c of the lid portion 68 (see FIG. 8) in the state in which the opening/closing member 78 is disposed at the closed position is defined as a facing portion 122. Thus, as illustrated in FIG. 14E, the projecting portion 146, the rib 144, the through hole 142, and the protrusion 140 are disposed on the other side relative to the facing portion 122 in the container circumferential direction.

The projecting portion 146, the rib 144, the through hole 142, and the protrusion 140 are arranged in this order from the rear part to the front part in the apparatus depth direction. In other words, the distance from the container portion 62 (see FIG. 12) increases in order from the projecting portion 146, the rib 144, the through hole 142, to the protrusion 140. That is, the projecting portion 146 is closest to the container portion 62 out of the projecting portion 146, the rib 144, the through hole 142, and the protrusion 140.

The protrusion 140 is disposed at a front part of the inner circumferential surface 120a of the curved plate 120 in the apparatus depth direction. As indicated by the two-dot chain line illustrated in FIG. 21, when the opening/closing member 78 is disposed at the closed position, the protrusion 140 is engaged with the recess 98a of the limiting portion 98. Such engagement between the protrusion 140 and the recess 98a of the limiting portion 98 limits the movement of the opening/closing member 78 relative to the lid portion 68 to the other side in the container circumferential direction. In other words, the engagement between the protrusion 140 and the recess 98a of the limiting portion 98 limits a movement of the lid portion 68 relative to the opening/closing member 78 to the one side in the container circumferential direction. In yet other words, the engagement between the protrusion 140 and the recess 98a of the limiting portion 98 limits the movements of the opening/closing member 78 and the lid portion 68 relative to each other in the container circumferential direction.

As illustrated in FIG. 14B, the through hole 142 has a rectangular shape extending in the container circumferential direction when seen from the outside in the container radial direction.

With this structure, as indicated by a two-dot chain line and a solid line illustrated in FIG. 20, from the outside of the opening/closing member 78, the limiting portion 98 is

13

pushed up toward the outer circumferential surface 72a of the second cylindrical portion 72 through the through hole 142. This causes the limiting portion 98 to be elastically deformed. As a result, as indicated by the solid line illustrated in FIG. 21, the engagement between the protrusion 140 and the recess 98a of the limiting portion 98 is released.

Furthermore, as illustrated in FIG. 14B, the rib 144 projects from an edge portion of the through hole 142 near the projecting portion 146. The rib 144 has a plate shape with a plate surface thereof facing the apparatus depth direction. The rib 144 is an example of a suppressing wall.

As illustrated in FIG. 14B, the projecting portion 146 is disposed on the opposite side to the through hole 142 with the rib 144 interposed therebetween in the apparatus depth direction. The projecting portion 146 has a rectangular shape extending in the container circumferential direction when seen from the inside in the container radial direction.

Furthermore, as illustrated in FIG. 14A, a recess 148 is formed in a portion of the outer circumferential surface 120b of the curved plate 120 corresponding to the projecting portion 146. That is, the projecting portion 146 has a box shape that is open toward the outside in the container radial direction.

As illustrated in FIG. 14B, a portion of the projecting portion 146 on the one side in the container circumferential direction is formed by the suppressing plate 150 having a plate surface that faces in the container circumferential direction. This suppressing plate 150 is disposed, in the container circumferential direction, on the one side relative to (closer to the facing portion 122 than) the through hole 142.

With this structure, when the opening/closing member 78 is disposed at the closed position, the suppressing plate 150 is in contact with the regulating projections 96 formed on the lid portion 68 in the container circumferential direction as illustrated in FIG. 19. Such contact between the suppressing plate 150 and the regulating projections 96 in the container circumferential direction regulates the movement of the opening/closing member 78 relative to the lid portion 68 to the one side in the container circumferential direction. In other words, the contact between the suppressing plate 150 and the regulating projections 96 in the container circumferential direction regulates the movement of the lid portion 68 relative to the opening/closing member 78 to the other side in the container circumferential direction. In yet other words, the contact between the suppressing plate 150 and the regulating projections 96 in the container circumferential direction regulates the movements of the opening/closing member 78 and the lid portion 68 relative to each other in the container circumferential direction.

Furthermore, two regulating projections 152 are provided and, as illustrated in FIG. 14A, project in the container radial direction from an end portion of the outer circumferential surface 120b of the curved plate 120 on the one side in the container circumferential direction. In other words, the distances between the central line CL01 and distal ends of the regulating projections 152 are larger than the distance between the central line CL01 and the outer circumferential surface 120b.

Specifically, in the state in which the container 60 is removed from the container mounting portion 82, the regulating projections 152 project in the opposite direction to the direction in which the gripping portion 74 projects. Furthermore, in the state in which the container 60 is disposed at the temporarily placed position, as illustrated in FIG. 19, the

14

regulating projections 152 project downward (in the direction in which the container 60 is moved) when seen in the apparatus depth direction.

As illustrated in FIG. 14A, two regulating projections 152 are respectively disposed on the one side and the other side relative to the facing portion 122 in the apparatus depth direction.

Others

As illustrated in FIG. 8, the distal end portion 76 of the lid portion 68 is, as described above, open at the front in the apparatus depth direction. A transmitting portion 88 is disposed in the distal end portion 76. The transmitting portion 88 transmits to the container portion 62 of the container 60 a rotating force for rotating the container portion 62 in the container circumferential direction. A sealing member (not illustrated) is provided in the lid portion 68 so as to suppress leakage of the toner to the outside through a gap between the transmitting portion 88 and the distal end portion 76.

With this structure, when the rotating force is transmitted to the container portion 62 through the transmitting portion 88, the container portion 62 is rotated in the container circumferential direction without rotating the lid portion 68. The Container Mounting Portion 82

As illustrated in FIG. 7, the container mounting portion 82 is formed in the unit body 80 of the image forming unit 18. The container mounting portion 82 extends in the apparatus depth direction and has a U shape that is open at the top. A first support portion 84 and a second support portion 86 are formed in the container mounting portion 82. The first support portion 84 supports the lid portion 68 of the container 60 (see FIG. 6) from below. The second support portion 86 has an arcuate shape in the section perpendicular to the longitudinal direction and supports the container portion 62 of the container 60 from below. The first support portion 84 and the second support portion 86 are arranged in this order from the front part to the rear part in the apparatus depth direction.

As illustrated in FIG. 15, the first support portion 84 has arcuate surfaces 84b, 84d having respective arcuate shapes and a rear surface 84c that is, in the apparatus depth direction, disposed in front of the arcuate surfaces 84a, 84b, 84d and faces rearward.

The arcuate surface 84a and the arcuate surface 84b are arranged in this order from the other side to the one side in the container circumferential direction. The arcuate surface 84d is disposed on the opposite side to the rear surface 84c with the arcuate surfaces 84a, 84b interposed therebetween in the apparatus depth direction and brought into contact with an outer circumferential surface 70b of the first cylindrical portion 70 of the lid portion 68 (see FIG. 8) so as to support the lid portion 68 from below.

Furthermore, the arcuate surface 84b has an opening 202 through which the toner is received from the container 60. The opening 202 has a rectangular shape extending in the apparatus depth direction when seen from the inside in the container radial direction.

Furthermore, as illustrated in FIG. 17, the first support portion 84 has an inhibiting portion 160. In the state in which the container 60 is disposed at the temporarily placed position, the inhibiting portion 160 enters the recess 148 formed in the opening/closing member 78 of the container 60 (see FIG. 14A) so as to inhibit the movement of the opening/closing member 78. Furthermore, the first support portion 84 has a releasing projection 162. In the state in which the container 60 is disposed at the temporarily placed position, the releasing projection 162 releases the engage-

15

ment between the protrusion 140 and the limiting portion 98 (see FIG. 21). The releasing projection 162 is an example of a releasing portion.

Furthermore, the first support portion 84 has a recess 166. In the state in which the container 60 is disposed at the temporarily placed position, the regulating projections 152 formed in the opening/closing member 78 (see FIG. 14A) enter the recess 166. Furthermore, the first support portion 84 includes a positioning mechanism 170 and an opening/closing member 174 (see FIGS. 15 and 16). The positioning mechanism 170 positions the container 60 mounted to the container mounting portion 82 relative to the container mounting portion 82. The opening/closing member 174 allows the opening 202 to be exposed and closes the opening 202 through which the toner is received from the container 60.

The Inhibiting Portion 160

As illustrated in FIG. 17, the inhibiting portion 160 projects upward from the arcuate surface 84a and has a trapezoidal shape when seen in the apparatus depth direction.

With this structure, as illustrated in FIG. 19, in the state in which the container 60 is disposed at the temporarily placed position, the inhibiting portion 160 enters the recess 148 formed in the opening/closing member 78. Thus, the inhibiting portion 160 is brought into contact with the suppressing plate 150 defining the recess 148 in the container circumferential direction, thereby inhibiting the movement of the opening/closing member 78 and the lid portion 68 to the other side in the container circumferential direction.

The Releasing Projection 162

As illustrated in FIG. 17, the releasing projection 162 projects upward from the arcuate surface 84a and is disposed in front of the inhibiting portion 160 in the apparatus depth direction. The releasing projection 162 has a triangular shape when seen in the apparatus depth direction.

With this structure, as illustrated in FIG. 20, in the state in which the container 60 is disposed at the temporarily placed position, the releasing projection 162 enters the through hole 142 formed in the opening/closing member 78. The releasing projection 162 pushes upward the limiting portion 98 of the lid portion 68. As a result, as indicated by the solid line illustrated in FIG. 21, the engagement between the protrusion 140 formed in the opening/closing member 78 and the recess 98a of the limiting portion 98 is released.

The Recess 166

As illustrated in FIG. 15, the recess 166 is formed between the arcuate surface 84a and the arcuate surface 84b in the container circumferential direction and extends in the apparatus depth direction. The recess 166 has a U shape in section that is open at the top. Furthermore, as illustrated in FIG. 20, a plate-shaped sponge material 168 is attached to a wall surface 166a that defines the recess 166 and faces the other side in the container circumferential direction. In the state in which the container 60 is disposed at the temporarily placed position, the sponge material 168 is separated from the regulating projections 152 formed in the opening/closing member 78 in the container circumferential direction. The sponge material 168 may be omitted from the drawings.

With this structure, in the state in which the container 60 is disposed at the temporarily placed position, the wall surface 166a defining the recess 166 faces, as illustrated in FIG. 20, an end surface 78a of the opening/closing member 78 on the one side in the container circumferential direction. The sponge material 168 is interposed between the wall surface 166a of the recess 166 and the end surface 78a of the

16

opening/closing member 78. In other words, in the state in which the container 60 is disposed at the temporarily placed position, the rotation of the opening/closing member 78 to the one side in the container circumferential direction is blocked by the wall surface 166a and the sponge material 168.

As has been described, the wall surface 166a and the sponge material 168 form a blocking section 124 that blocks the rotation of the opening/closing member 78 to the one side in the container circumferential direction in the state in which the container 60 is disposed at the temporarily placed position.

Furthermore, although the details will be described later, when the container 60 disposed at a position deviated from the temporarily placed position is rotated to the one side in the container circumferential direction, as illustrated in FIG. 28, the regulating projections 152 of the opening/closing member 78 push the sponge material 168 attached to the wall surface 166a. The wall surface 166a of the recess 166 and the sponge material 168 regulate the movement of the opening/closing member 78 to the one side in the container circumferential direction.

As has been described, the wall surface 166a and the sponge material 168 form an engagement section 154 that is brought into engagement with the regulating projections 152 when the container 60 is rotated to the one side in the container circumferential direction in the state in which the container 60 is disposed at a position deviated from the temporarily placed position. In this way, the regulating projections 152 function as rotation regulating members that regulate the rotation to the one side in the container circumferential direction.

Furthermore, as has been described, the regulating projections 152 are respectively disposed on the one side and the other side relative to the facing portion 122 in the apparatus depth direction. This suppresses inclination of the opening/closing member 78 relative to the container circumferential direction when the regulating projections 152 push the sponge material 168 attached to the wall surface 166a compared to the case where a single regulating projection is formed. From the viewpoint of suppressing the inclination of the opening/closing member 78 relative to the container circumferential direction, the pitch of two regulating projections 152 may be increased. That is, the regulating projections 152 may be formed at respective end portions of the opening/closing member 78 in the apparatus depth direction.

The Positioning Mechanism 170

As illustrated in FIG. 16, the positioning mechanism 170 has an intersecting surface 180 that is disposed between the arcuate surface 84a and the rear surface 84c in the apparatus depth direction and extends in a direction intersecting the apparatus depth direction (apparatus up-down direction).

The container 60 is disposed at the temporarily placed position by bringing the guide surface 108 of the lid portion 68 (see FIG. 11) into contact with this intersecting surface 180. The positioning mechanism 170 further has a contact surface 182. The contact surface 182 is disposed between the arcuate surface 84a and the rear surface 84c in the apparatus depth direction and is, in the state in which the container 60 is disposed at the mounted position, in contact with the contact surface 104 of the lid portion 68 (see FIG. 9).

The positioning mechanism 170 further has a contact surface 186 as illustrated in FIG. 17. The contact surface 186 is disposed between the arcuate surface 84a and the rear surface 84c in the apparatus depth direction and is, in the

state in which the container 60 is disposed at the mounted position, in contact with the contact surface 102 of the lid portion 68 (see FIG. 10).

The positioning mechanism 170 further has a contact surface 196 as illustrated in FIG. 15. The contact surface 196 is disposed in a portion behind the arcuate surface 84b in the apparatus depth direction and is, in the state in which the container 60 is disposed at the mounted position, in contact with the contact surface 106 of the lid portion 68 (see FIG. 8).

The Intersecting Surface 180 and the Contact Surface 182

As illustrated in FIG. 16, the intersecting surface 180 and the contact surface 182 are disposed on the other side relative to the central line CL01 in the apparatus width direction and are adjacent to each other from the upper side to lower side in this order.

The intersecting surface 180 has a flat shape and extends in the apparatus up-down direction that is a direction intersecting the apparatus depth direction. The intersecting surface 180 faces the one side in the apparatus width direction. Furthermore, when seen in the direction in which the intersecting surface 180 faces, the intersecting surface 180 has a rectangular shape extending in the apparatus up-down direction. This contact surface 182 has an arcuate shape centered at the central line CL01 when seen in the apparatus depth direction and faces inward in the container radial direction.

As illustrated in FIG. 18, with this structure, when the container 60 is moved with the guide surface 108 and the intersecting surface 180 in contact with each other, the container 60 is moved in the apparatus up-down direction. Then, the container 60 is moved downward in the apparatus up-down direction so as to be disposed at the temporarily placed position.

Furthermore, when the container 60 disposed at the temporarily placed position is rotated to the one side in the container circumferential direction so as to be disposed at the mounted position, the contact surface 104 of the lid portion 68 is brought into contact with the contact surface 182 of the container mounting portion 82 as illustrated in FIG. 23. Specifically, the contact surface 104 of the lid portion 68 is brought into surface contact with the contact surface 182 from the inside (a position near the central line CL01) relative to the contact surface 182 in the container radial direction.

Thus, the contact surface 104 and the contact surface 182 form a contact section 184 where the container 60 is in contact with the container mounting portion 82 from inside in the container radial direction. That is, the contact section 184 functions as a movement regulating section that regulates the movement of the container 60 toward the container mounting portion 82.

The Contact Surface 186 and Others

As illustrated in FIG. 17, the contact surface 186 is disposed on the one side relative to the central line CL01 in the apparatus width direction. The contact surface 186 has an arcuate shape centered at the central line CL01 when seen in the apparatus depth direction and faces inward in the container radial direction.

Furthermore, an auxiliary surface 188 having a curved shape is formed on the other side relative to the contact surface 186 in the container circumferential direction. The auxiliary surface 188 is disposed at a region having a larger diameter than that of the contact surface 186.

With this structure, as illustrated in FIG. 18, in the state in which the container 60 is disposed at the temporarily placed position, the contact surface 102 of the lid portion 68 and the auxiliary surface 188 are kept separated from each

other in the container radial direction. Furthermore, when the container 60 disposed at the temporarily placed position is rotated to the one side in the container circumferential direction so as to be disposed at the mounted position, the contact surface 102 of the lid portion 68 is brought into contact with the contact surface 186 of the container mounting portion 82 as illustrated in FIG. 23. Specifically, the contact surface 102 of the lid portion 68 is brought into surface contact with the contact surface 186 from the inside (a position near the central line CL01) relative to the contact surface 186 in the container radial direction.

Thus, the contact surface 102 and the contact surface 186 form a contact section 192 where the container 60 is in contact with the container mounting portion 82 from inside in the container radial direction. That is, the contact section 192 functions as a movement regulating section that regulates the movement of the container 60 toward the container mounting portion 82.

The Contact Surface 196

The contact surface 196 is formed at a portion in front of the arcuate surface 84b in the apparatus depth direction. As illustrated in FIG. 15, the contact surface 196 is disposed, in the container circumferential direction, at a position on the one side relative to the contact surface 186 and on the other side relative to the contact surface 182. The contact surface 196 has an arcuate shape centered at the central line CL01 when seen in the apparatus depth direction and faces outward in the container radial direction.

With this structure, as illustrated in FIG. 22, in the state in which the container 60 is disposed at the temporarily placed position, the contact surface 106 of the lid portion 68 and the contact surface 196 of the container mounting portion 82 are kept separated from each other in the container circumferential direction. Furthermore, when the container 60 disposed at the temporarily placed position is rotated to the one side in the container circumferential direction so as to be disposed at the mounted position, as illustrated in FIG. 24, the contact surface 106 of the lid portion 68 is inserted into a guide groove 204 (see FIG. 15), which will be described later. Thus, the contact surface 106 of the lid portion 68 is brought into contact with the contact surface 196 of the container mounting portion 82. Specifically, the contact surface 106 of the lid portion 68 is brought into surface contact with the contact surface 196 from the outside relative to the contact surface 196 in the container radial direction.

Thus, the contact surface 106 and the contact surface 196 form a contact section 198 where the container 60 is in contact with the container mounting portion 82 from outside in the container radial direction. That is, the contact section 198 functions as a movement regulating section that regulates the movement of the container 60 toward a region separating from the container mounting portion 82.

As has been described, in the state in which the container 60 is disposed at the mounted position, the container 60 and the container mounting portion 82 are in contact with each other in the container radial direction at three contact sections 184, 192, 198 in the container circumferential direction. Thus, the container 60 is positioned relative to the container mounting portion 82 in the container radial direction. Here, from the viewpoint of improving the function of positioning the container 60 relative to the container mounting portion 82, the central angle between the contact section 184 and the contact section 198 and the central angle between the contact section 192 and the contact section 198 when seen in the apparatus depth direction may be large. Specifically, it is preferable that these central angles be 50

degrees or larger, it is more preferable that these central angles be 60 degrees or larger, and it is particularly preferable that these central angles be 70 degrees or larger. According to the present exemplary embodiment, these central angles are set to be 70 degrees or larger.

Furthermore, the transmitting portion 88 is disposed at the front part of the container 60 in the apparatus depth direction as has been described (see FIG. 8). The transmitting portion 88 transmits to the container portion 62 of the container 60 a rotating force for rotating the container portion 62 in the container circumferential direction. All the contact sections 184, 192, 198 are formed in a front region in the apparatus depth direction of the container 60. In other words, all the contact sections 184, 192, 198 are formed in a region where the transmitting portion 88 is disposed in the container 60.

Here, the front region in the apparatus depth direction of the container 60 refers to a region within 30% from a front end portion of the container 60 in the apparatus depth direction when the length of the container 60 in the apparatus depth direction is 100%. Here, since the rotating force is transmitted in the front region in the apparatus depth direction of the container 60, the transmission path may be deviated. In order to suppress the deviation of the transmission path, when the length of the container 60 in the apparatus depth direction is 100%, in the apparatus depth direction of the container 60, it is preferable that all the contact sections 184, 192, 198 be disposed in a region within 20% from the front end portion of the container 60, it is more preferable that all the contact sections 184, 192, 198 be disposed in a region within 15% from the front end portion of the container 60, and it is particularly preferable that all the contact sections 184, 192, 198 be disposed in a region within 10% from the front end portion of the container 60.

Others

As illustrated in FIG. 15, the rear surface 84c has a circular hole 210 centered at the central line CL01. The container mounting portion 82 includes a transmitting portion 212 that projects toward the container 60 disposed at the mounted position through the circular hole 210 so as to transmit the rotating force to the transmitting portion 88 (see FIG. 8) of the container 60.

With this structure, when the container 60 disposed at the temporarily placed position is rotated to the one side in the container circumferential direction so as to be disposed at the mounted position, a mechanical structure (not illustrated) is operated so as to cause the transmitting portion 212 to project through the circular hole 210. Thus, the transmitting portion 212 is brought into engagement with the transmitting portion 88 of the container 60. In this way, the transmitting portion 212 rotated by a motor (not illustrated) transmits the rotating force to the transmitting portion 88. In contrast, when the container 60 disposed at the mounted position is rotated to the other side in the container circumferential direction so as to be disposed at the temporarily placed position, the transmitting portion 212 does not project through the circular hole 210.

Furthermore, as illustrated in FIG. 17, the container mounting portion 82 includes a holding portion 216 that holds the container 60 disposed at the mounted position. The holding portion 216 is disposed in front of the arcuate surface 84a in the apparatus depth direction and on the one side relative to the central line CL01 in the apparatus width direction. The holding portion 216 extends in the up-down direction. The holding portion 216 has a cantilever shape in which an upper end is a free end. The holding portion 216 has a projection 216a projecting toward the central line CL01 at its upper end portion.

With this structure, when the container 60 is disposed at the temporarily placed position, as illustrated in FIG. 26A, the extended surface 72d of the lid portion 68 is brought into contact with the projection 216a of the holding portion 216. This causes the holding portion 216 to be bent and elastically deformed about a base end portion. Furthermore, when the container 60 disposed at the temporarily placed position is rotated to the one side in the container circumferential direction so as to be disposed at the mounted position, as illustrated in FIG. 26B, the projection 216a and the extended surface 72d are separated from each other in the container circumferential direction, thereby the holding portion 216 is elastically returned to its original shape. In this state, when the projection 216a of the holding portion 216 covers, from above, a portion of the lid portion 68 where the extended surface 72d is formed, the holding portion 216 holds the container 60 disposed at the mounted position. When the holding portion 216 is elastically deformed, a force acts on the container 60 in a direction in which the container 60 is separated from the container mounting portion 82.

Furthermore, as illustrated in FIG. 17, the container mounting portion 82 has a marked surface 172 extending from an upper edge portion of the rear surface 84c toward the front in the apparatus depth direction. The marked surface 172 is an arcuate surface facing outward in the container radial direction. The marked surface 172 has triangular marks 172a and 172b the vertices of which point toward the rear in the apparatus depth direction. The mark 172a and the mark 172b are kept separated from each other in the container circumferential direction and arranged in this order from the other side to the one side in the container circumferential direction.

With this structure, as illustrated in FIG. 5, in the state in which the container 60 is disposed at the temporarily placed position, the mark 112a of the container 60 and the mark 172a of the container mounting portion 82 face each other in the apparatus depth direction. In contrast, as illustrated in FIG. 4, in the state in which the container 60 is disposed at the mounted position, the mark 112a of the container 60 and the mark 172b of the container mounting portion 82 face each other in the apparatus depth direction.

The Opening/Closing Member 174 and Others

The opening/closing member 174 is mounted to the arcuate surface 84b and, as illustrated in FIG. 15, moved to an open position where the opening/closing member 174 allows the opening 202 formed in the arcuate surface 84b to be exposed and a closed position (see FIG. 16) where the opening/closing member 174 closes the opening 202. The opening/closing member 174 is a plate having an arcuate shape along the arcuate surface 84b and has a rectangular shape extending in the apparatus circumferential direction when seen from the inside in the container radial direction.

The arcuate surface 84b has a pair of guide grooves 204 and 206 kept separated from each other in the apparatus depth direction. The guide grooves 204 and 206 guide the opening/closing member 174 in the container circumferential direction.

The guide groove 204 extends in the container circumferential direction in a portion of the arcuate surface 84b near the rear surface 84c and has a U shape in section which is open at the rear in the apparatus depth direction (portion near the opening 202). The guide groove 204 is provided with the above-described contact surface 196 facing outward in the container radial direction.

The guide groove 206 extends in the container circumferential direction in a portion opposite to the guide groove 204 with the opening 202 interposed therebetween in the

apparatus depth direction and has a U shape in section which is open at the front in the apparatus depth direction (a portion near the opening 202).

A front edge portion of the opening/closing member 174 in the apparatus depth direction is inserted into the guide groove 204, and a rear edge portion of the opening/closing member 174 in the apparatus depth direction is inserted into the guide groove 206.

With this structure, as illustrated in FIG. 19, in a state in which the opening/closing member 174 is disposed at the closed position and the container 60 is disposed at the temporarily placed position, the container 60 is rotated to the one side in the container circumferential direction so as to be moved to the mounted position. Consequently, as illustrated in FIG. 25, the opening/closing member 174 is pushed to the one side in the container circumferential direction by an end surface of the step portion 72b formed in the lid portion 68 so as to be moved from the closed position to the open position.

In contrast, when the container 60 disposed at the mounted position is rotated to the other side in the container circumferential direction so as to be moved to the temporarily placed position, the opening/closing member 174 is pushed to the other side in the container circumferential direction by a projection (not illustrated) formed in the lid portion 68 so as to be moved from the open position to the closed position.

Operations of the Elements

Next, operations of the elements are described. First, a container mounting structure 552 according to a comparative embodiment is described by focusing on the difference between the container mounting structure 552 according to the comparative embodiment and the container mounting structure 52 according to the present exemplary embodiment. Also, operations of the container mounting structure 552 are described by focusing on the difference between the operations of the container mounting structure 552 and operations of the container mounting structure 52 according to the present exemplary embodiment.

The Container Mounting Structure 552

As illustrated in FIGS. 27 and 28, a distal end portion 576 of a lid portion 568 of a container 560 included in the container mounting structure 552 has a contact surface 502 to be in contact with a container mounting portion 582 so as to position the container 560 relative to the container mounting portion 582.

The contact surface 502 is disposed, in the container circumferential direction, at a position on the other side relative to the contact surface 104 and on the one side relative to the contact surface 102. Furthermore, in the container radial direction, the contact surface 502 projects outward from the arcuate surface 116 so as to face outward. Furthermore, the contact surface 502 has a smaller diameter than that of the outer circumferential surface 72a of the second cylindrical portion 72. This contact surface 502 has an arcuate shape centered at the central line CL01 when seen in the apparatus depth direction. Furthermore, as illustrated in FIG. 29, the container mounting portion 582 further has a contact surface 584 that is, in the state in which the container 560 is disposed at the mounted position, in surface contact with the contact surface 502 of the lid portion 568. This contact surface 584 has an arcuate shape centered at the central line CL01 when seen in the apparatus depth direction.

Furthermore, as illustrated in FIG. 30, in a state in which the container 560 is disposed at the mounted position, the contact surface 596 of the container mounting portion 582 is

disposed inside the contact surface 106 of the lid portion 568 in the container radial direction. That is, the contact surface 106 of the lid portion 568 and the contact surface 596 of the container mounting portion 582 are kept separated from each other in the container radial direction.

As described above, in the container mounting structure 552, in order to position the container 560 relative to the container mounting portion 582, the container 560 is in contact with the container mounting portion 582 from inside in the container radial direction at all contact sections.

Operations of the Container Mounting Structures 52, 552

In order to mount the container 60 to the container mounting portion 82 formed in the unit body 80, as illustrated in FIG. 6, the container 60 is oriented such that the distal end of the gripping portion 74 of the container 60 faces upward. In the state in which the container 60 is removed from the container mounting portion 82, the opening/closing members 78, 174 is disposed at the closed position (see FIGS. 10 and 16). Furthermore, the protrusion 140 formed in the opening/closing member 78 and the recess 98a of the limiting portion 98 are engaged with each other (see the two-dot chain line in FIG. 21).

Then, as illustrated in FIGS. 5 and 6, with the above-described orientation maintained, the container 60 is moved downward (in a direction intersecting the apparatus depth direction) from a position above the unit body 80 such that the container 60 approaches the container mounting portion 82.

Furthermore, as indicated by the two-dot chain line and the solid line illustrated in FIG. 18, the container 60 is moved downward while the guide surface 108 of the container 60 being in contact with the intersecting surface 180 of the container mounting portion 82. Then, when the outer circumferential surface 70b (see FIG. 12) of the first cylindrical portion 70 of the lid portion 68 is brought into contact with (placed on) the arcuate surface 84d (see FIG. 17) of the container mounting portion 82, the container 60, 560 is disposed at the temporarily placed position as illustrated in FIGS. 18 and 28.

As illustrated in FIG. 5, in the state in which the container 60 is disposed at the temporarily placed position, the mark 112a of the container 60 and the mark 172a of the container mounting portion 82 face each other in the apparatus depth direction. Furthermore, in this state, as illustrated in FIG. 26A, the extended surface 72d of the lid portion 68 is brought into contact with the projection 216a of the holding portion 216. This causes the holding portion 216 to be bent and elastically deformed about the base end portion.

Furthermore, as illustrated in FIG. 20, in the state in which the container 60 is disposed at the temporarily placed position, the sponge material 168 attached to the wall surface 166a is in contact with the opening/closing member 78 in the container circumferential direction. Thus, the wall surface 166a of the recess 166 and the sponge material 168 regulate the movement of the opening/closing member 78 to the one side in the container circumferential direction.

Furthermore, the releasing projection 162 enters the through hole 142 formed in the opening/closing member 78 so as to push upward the limiting portion 98 of the lid portion 68. As a result, as indicated by the solid line illustrated in FIG. 21, the limiting portion 98 is elastically deformed so as to release the engagement between the protrusion 140 formed in the opening/closing member 78 and the recess 98a of the limiting portion 98 (see FIG. 21).

Furthermore, when the gripping portion 74 is gripped and the container 60 disposed at the temporarily placed position is rotated to the one side in the container circumferential

direction, as illustrated in FIG. 26B, the projection 216a and the extended surface 72d are separated from each other in the container circumferential direction, thereby the holding portion 216 is elastically returned to its original shape. In this state, when the projection 216a of the holding portion 216 covers, from above, the portion of the lid portion 68 where the extended surface 72d is formed, the holding portion 216 holds the container 60 disposed at the mounted position.

Furthermore, when the container 60 disposed at the temporarily placed position is rotated to the one side in the container circumferential direction, as illustrated in FIG. 25, the opening/closing member 174 is pushed to the one side in the container circumferential direction by the end surface of the step portion 72b formed in the lid portion 68, thereby the opening/closing member 174 is moved from the closed position to the open position. Furthermore, as illustrated in FIG. 20, since the movement of the opening/closing member 78 to the one side in the container circumferential direction is regulated by the sponge material 168 and the wall surface 166a, the opening/closing member 78 is moved from the closed position to the open position. Thus, as illustrated in FIG. 25, the opening 72c formed in the lid portion 68 and the opening 202 formed in the container mounting portion 82 face each other.

An angle by which the container 60 is rotated is regulated by a stopper (not illustrated). Thus, the container 60 is disposed at the mounted position. As illustrated in FIG. 4, in the state in which the container 60 is disposed at the mounted position, the mark 112a of the container 60 and the mark 172b of the container mounting portion 82 face each other in the apparatus depth direction.

Here, as illustrated in FIG. 29, in the state in which the container 560 of the container mounting structure 552 according to the comparative embodiment is disposed at the mounted position, the contact surface 104 of the lid portion 568 is in contact with the contact surface 182 of the container mounting portion 582 from inside in the container radial direction. Furthermore, the contact surface 102 of the lid portion 568 is in contact with the contact surface 186 of the container mounting portion 582 from inside in the container radial direction. Furthermore, the contact surface 502 of the lid portion 568 is in contact with the contact surface 584 of the container mounting portion 582 from inside in the container radial direction.

As described above, in the container mounting structure 552 according to the comparative embodiment, all the contact surfaces 104, 102, 502 are in contact with the contact surfaces 182, 186, 584 of the container mounting portion 582 from inside in the container radial direction. Thus, the container 560 is positioned relative to the container mounting portion 582.

Meanwhile, as illustrated in FIG. 23, in the state in which the container 60 of the container mounting structure 52 according to the present exemplary embodiment is disposed at the mounted position, the contact surfaces 104, 102 of the lid portion 68 is in contact with the contact surfaces 182, 186 of the container mounting portion 82 from inside in the container radial direction. Furthermore, as illustrated in FIG. 24, the contact surface 106 of the lid portion 68 is in contact with the contact surface 196 of the container mounting portion 82 from outside in the container radial direction.

As described above, in the container mounting structure 52 according to the present exemplary embodiment, the container 60 is in contact with the container mounting portion 82 from inside in the container radial direction at two contact sections 184, 192 and in contact with the container

mounting portion 82 from outside in the container radial direction at a single contact section 198. Thus, the container 60 is positioned relative to the container mounting portion 82.

Furthermore, when the container 60 is disposed at the mounted position, the transmitting portion 212 of the container mounting portion 82 (see FIG. 15) projects through the circular hole 210. Thus, the transmitting portion 212 is brought into engagement with the transmitting portion 88 of the container 60 (see FIG. 8). In this way, the transmitting portion 212 rotated by the motor (not illustrated) transmits the rotating force to the transmitting portion 88.

Furthermore, the container portion 62 of the container 60 disposed at the mounted position illustrated in FIG. 4 is rotated in the container circumferential direction. This causes the toner contained in the container portion 62 to be pushed by the projection 66 projecting from the inner circumferential surface 62c of the container portion 62 (see FIG. 12). Thus, the toner is moved from the rear part to the front part in the apparatus depth direction. The toner having been moved to the front part in the apparatus depth direction is supplied to the developing device 40 through the opening 72c formed in the lid portion 68 and the opening 202 formed in the container mounting portion 82 illustrated in FIG. 25.

Furthermore, in order to remove the container 60 from the container mounting portion 82 formed in the unit body 80, the gripping portion 74 is gripped and the container 60 disposed at the mounted position is rotated to the other side in the container circumferential direction. When the container 60 is rotated to the other side in the container circumferential direction, as illustrated in FIG. 26A, the extended surface 72d of the lid portion 68 is brought into contact with the projection 216a of the holding portion 216. This causes the holding portion 216 to be bent and elastically deformed about the base end portion.

Furthermore, even when the container 60 is rotated to the other side in the container circumferential direction, as illustrated in FIG. 19, the movement of the opening/closing member 78 to the other side in the container circumferential direction is inhibited by the inhibiting portion 160. Accordingly, the regulating projections 96 formed in the lid portion 68 push the inhibiting portion 160 of the container mounting portion 82 with the suppressing plate 150 of the opening/closing member 78 interposed therebetween so as to regulate the angle by which the container 60 is rotated. Thus, the container 60 is moved to the temporarily placed position.

Furthermore, as indicated by the two-dot chain line and the solid line illustrated in FIG. 18, when the container 60 disposed at the temporarily placed position is moved upward while the guide surface 108 of the container 60 being in contact with the intersecting surface 180 of the container mounting portion 82, the container 60 is removed from the container mounting portion 82.

Furthermore, when the container 60 is moved upward from the temporarily placed position, the releasing projection 162 illustrated in FIG. 20 is separated from the limiting portion 98 of the lid portion 68, thereby the limiting portion 98 is elastically returned to its original shape. When the limiting portion 98 is elastically returned to its original shape, as indicated by the two-dot chain line illustrated in FIG. 21, the recess 98a of the limiting portion 98 is brought into engagement with the protrusion 140 of the opening/closing member 78. Thus, the movement of the opening/closing member 78 relative to the lid portion 68 is limited, and the state in which the opening/closing member 78 is disposed at the closed position is maintained.

Summarization

As has been described, in the container mounting structure 52, the container 60 is in contact with the container mounting portion 82 from inside in the container radial direction at two contact sections 184, 192 and in contact with the container mounting portion 82 from outside in the container radial direction at a single contact section 198. Thus, compared to the case with the container mounting structure 552 where the container is in contact with the container mounting portion from inside in the container radial direction at all the contact sections, accuracy of positioning of the container 60 relative to the container mounting portion 82 may be improved by regulating movements of the container 60 inward and outward in the container radial direction.

Furthermore, in the container mounting structure 52, the contact section 198 where the contact surface 106 of the lid portion 68 is in contact with the contact surface 196 of the container mounting portion 82 from outside in the container radial direction is, when seen in the apparatus depth direction, superposed on the opening 72c of the lid portion 68 in the container circumferential direction. Thus, compared to the case where all the contact sections are disposed at different positions from the position of the opening 72c in the container circumferential direction, accuracy of the position of the opening 72c relative to the container mounting portion 82 in the container radial direction may be improved.

Furthermore, in the container mounting structure 52, the contact section 198 where the contact surface 106 of the lid portion 68 is in contact with the contact surface 196 of the container mounting portion 82 from outside in the container radial direction is, when seen in the apparatus depth direction, superposed on the opening 72c of the lid portion 68 in the container circumferential direction. This may reduce the likelihood of the opening 72c separating from the container mounting portion 82 compared to the case where the container is in contact with the container mounting portion from inside in the container radial direction at a contact section superposed on the opening 72c in the container circumferential direction.

Furthermore, in the container mounting structure 52, the lid portion 68 of the container 60 has the guide surface 108 to be brought into surface contact with the intersecting surface 180 of the container mounting portion 82 so as to guide the container 60 to the temporarily placed position. The lid portion 68 of the container 60 further has the contact surface 104 that is, in the state in which the container 60 is disposed at the mounted position, in contact with the contact surface 182 of the container mounting portion 82 (see FIGS. 18 and 23). The guide surface 108 and the contact surface 104 formed in the lid portion 68 are adjacent to each other. This may improve relative positional accuracy between the guide surface 108 and the contact surface 104 compared to the case where the guide surface is spaced from the contact surface.

Furthermore, in the container mounting structure 52, the container mounting portion 82 has the intersecting surface 180 to be brought into surface contact with the guide surface 108 of the lid portion 68 so as to guide the container 60 to the temporarily placed position. Furthermore, the container mounting portion 82 has the contact surface 182 that is, in the state in which the container 60 is disposed at the mounted position, in contact with the contact surface 104 of the lid portion 68 (see FIGS. 18 and 23). The intersecting surface 180 and the contact surface 182 formed in the container mounting portion 82 are adjacent to each other.

This may improve relative positional accuracy between the intersecting surface 180 and the contact surface 182 compared to the case where the intersecting surface and the contact surface are spaced from each other.

Furthermore, in the container mounting structure 52, the rotating force (motive force) for transporting, in the apparatus depth direction, the toner contained in the container 60 is transmitted from the container mounting portion 82 to the container 60 through the front part of the container 60 in the apparatus depth direction. In addition, all the contact sections 184, 192, 198 are disposed in the front region in the apparatus depth direction of the container 60.

This may improve relative positional accuracy between the front part of the container 60 in the apparatus depth direction and the container mounting portion 82 compared to the case where all the contact sections are disposed on the opposite side to the side where the rotating force is transmitted from the container mounting portion. This may, in turn, suppress the occurrences of failure in transmission of the rotating force caused by deviation of the transmission path of the rotating force compared to the case where all the contact sections are disposed at part on the opposite side to the part to which the rotating force is transmitted from the container mounting portion.

Furthermore, in the container mounting structure 52, the contact surface 106 included in the positioning mechanism 170 defines the guide groove 92 through which the opening/closing member 78 is guided. This may simplify the shape compared to the case where the guide groove and the contact surface are separately provided. Furthermore, the contact surface 196 included in the positioning mechanism 170 defines the guide groove 204 through which the opening/closing member 174 is guided. This may simplify the shape compared to the case where the guide groove and the contact surface are separately provided.

Furthermore, in the image forming unit 18, compared to the case where the container is in contact with the container mounting portion from inside in the container radial direction at all the contact sections, accuracy in positioning the container relative to the container mounting portion may be improved, and accordingly, the occurrences of failure in supply of the toner to the developing device 40 may be suppressed.

Furthermore, in the image forming apparatus 10, compared to the case where the container is in contact with the container mounting portion from inside in the container radial direction at all the contact sections, the movements of the container 60 inward and outward in the container radial direction is suppressed, and accordingly, when the image forming unit 18 is mounted to or removed from the apparatus body 12, deviation of the container 60 from the container mounting portion 82 may be suppressed.

Furthermore, in the image forming apparatus 10, compared to the case where the container is in contact with the container mounting portion from inside in the container radial direction at all the contact sections, the occurrences of failure in supply of the toner to the developing device 40 may be suppressed, and accordingly, the occurrences of problems in quality of output images may be suppressed.

Although the present disclosure has been described in detail with the specific exemplary embodiment, the present disclosure is not limited to this exemplary embodiment. It is obvious to one skilled in the art that various other exemplary embodiments are possible within the scope of the present disclosure. For example, although three contact sections

184, 192, 198 are provided according to the above-described exemplary embodiment, four or more contact sections may be provided.

Furthermore, according to the above-described exemplary embodiment, the contact section 198 where the container is in contact with the container 60 mounting portion 82 from outside in the container radial direction is, when seen in the apparatus depth direction, superposed on the opening 72c in the container circumferential direction. However, the contact section 184, 192 where the container 60 is in contact with the container mounting portion 82 from inside in the container radial direction may be superposed on the opening 72c in the container circumferential direction. This may reduce the likelihood of reduction in the distance between the opening 72c and the container mounting portion to a value smaller than a target value in the design.

Furthermore, although it is not particularly described for the above-described exemplary embodiment, accuracy of guiding the container 60 to the temporarily placed position may be improved by forming, on the guide surface 108, a protrusion extending in the up-down direction and forming, in the intersecting surface 180, a recess that allows the protrusion to be inserted thereinto such that the protrusion is movable in the up-down direction.

Furthermore, according to the above-described exemplary embodiment, there are provided two contact sections where the container 60 is in contact with the container mounting portion 82 from inside in the container radial direction and a single contact section where the container 60 is in contact with the container mounting portion 82 from outside in the container radial direction. However, there may be provided a single contact section where the container is in contact with the container mounting portion from inside in the container radial direction and two contact sections where the container is in contact with the container mounting portion from outside in the container radial direction.

Furthermore, although the guide surface 108 and the contact surface 104 formed in the lid portion 68 are adjacent to each other according to the above-described exemplary embodiment, the guide surface and the contact surface may be spaced from each other. In this case, however, the features obtained when the guide surface 108 and the contact surface 104 are adjacent to each other are not obtained.

Furthermore, although the intersecting surface 180 and the contact surface 182 formed in the container mounting portion 82 are adjacent to each other according to the above-described exemplary embodiment, the intersecting surface and the contact surface may be spaced from each other. In this case, however, the features obtained when the intersecting surface 180 and the contact surface 182 are adjacent to each other are not obtained.

The foregoing description of the exemplary embodiment of the present disclosure has been provided for the purposes of illustration and description. It is not intended to be exhaustive or to limit the disclosure to the precise forms disclosed. Obviously, many modifications and variations will be apparent to practitioners skilled in the art. The embodiment was chosen and described in order to best explain the principles of the disclosure and its practical applications, thereby enabling others skilled in the art to understand the disclosure for various embodiments and with the various modifications as are suited to the particular use contemplated. It is intended that the scope of the disclosure be defined by the following claims and their equivalents.

What is claimed is:

1. A container mounting structure comprising:
a container that extends in one direction and that contains powder; and
a container mounting portion to which the container is mounted by rotating the container disposed at a temporarily placed position in a circumferential direction of the container;
wherein, in a state in which the container is mounted to the container mounting portion, the container mounting structure has contact sections where the container is in contact with the container mounting portion in a radial direction of the container, and each of the contact sections is disposed at a corresponding one of at least three different positions in the circumferential direction, and
wherein the container is in contact with the container mounting portion from inside in the radial direction at one subset of the contact sections and from outside in the radial direction at another subset of the contact sections,
wherein the one subset of the contact sections and the other subset of the contact sections are disposed at different positions in the one direction.
2. The container mounting structure according to claim 1, wherein the container includes
a container body having an opening through which the powder contained in the container is discharged to outside of the container, and
an opening/closing member that is movable in the circumferential direction relative to the container body so as to allow the opening to be exposed and close the opening, and
wherein, when seen in the one direction, one of the contact sections is superposed on the opening in the circumferential direction.
3. The container mounting structure according to claim 2, wherein, at the one of the contact sections where the one of the contact sections is superposed on the opening in the circumferential direction, the container is in contact with the container mounting portion from outside in the radial direction.
4. The container mounting structure according to claim 1, wherein the container is disposed at the temporarily placed position when the container is moved from outside toward the container mounting portion in an intersecting direction that intersects the one direction, wherein the container mounting portion has an intersecting surface that extends in the intersecting direction, and
wherein the container has a guide surface that is brought into surface contact with the intersecting surface so as to guide the container to the temporarily placed position and a contact surface that is adjacent to the guide surface and that forms one of the contact sections.
5. The container mounting structure according to claim 1, wherein a motive force for transporting the powder contained in the container in the one direction is transmitted to the container through a part at one side of the container in the one direction, and
wherein all the contact sections are disposed in a region at or around the one side of the container in the one direction.
6. An image forming unit comprising:
a developing section that develops with toner as the powder an electrostatic latent image formed on an image holding body so as to obtain a toner image; and
the container mounting portion to which the container containing the powder to be supplied to the developing

29

section is mounted by using the container mounting structure according to claim 1, wherein the image forming unit is removably mountable to an apparatus body.

7. An image forming apparatus comprising:
the apparatus body;
the image forming unit according to claim 6 removably mountable to the apparatus body; and
a transport section that transports a recording medium to which the toner image formed on the image holding body by the image forming unit is transferred.

8. An image forming apparatus comprising:
an image holding body that holds an electrostatic latent image;
a developing section that develops with toner as the powder the electrostatic latent image formed on the image holding body so as to obtain a toner image;
the container mounting portion to which the container containing the powder to be supplied to the developing section is mounted by using the container mounting structure according to claim 1; and
a transport section that transports a recording medium to which the toner image formed on the image holding body is transferred.

9. A container mounting structure comprising:
a container that extends in one direction and that contains powder; and

a container mounting portion to which the container is mounted by rotating the container disposed at a temporarily placed position in a circumferential direction of the container;

wherein, in a state in which the container is mounted to the container mounting portion, the container mounting structure has contact sections where the container is in contact with the container mounting portion in a radial direction of the container, and each of the contact sections is disposed at a corresponding one of at least three different positions on at least one circumferential surface of the container in the circumferential direction, and

wherein the container is in contact with the container mounting portion from inside in the radial direction at one subset of the contact sections and from outside in the radial direction at another subset of the contact sections,

wherein the one subset of the contact sections and the other subset of the contact sections are disposed at different positions in the one direction.

10. A container mounting structure comprising:
a container that extends in one direction and that contains powder; and
a container mounting portion to which the container is mounted by rotating the container disposed at a temporarily placed position in a circumferential direction of the container;

wherein, in a state in which the container is mounted to the container mounting portion, the container mounting structure has contact sections where the container is in contact with the container mounting portion in a radial direction of the container, and each of the contact sections is disposed at a corresponding one of at least three different positions in the circumferential direction,

wherein the container is in contact with the container mounting portion from inside in the radial direction at one subset of the contact sections and from outside in the radial direction at another subset of the contact sections,

wherein the container is disposed at the temporarily placed position when the container is moved from outside toward the container mounting portion in an intersecting direction that intersects the one direction, wherein the container mounting portion has an intersecting surface that extends in the intersecting direction, wherein the container has a guide surface that is brought into surface contact with the intersecting surface so as to guide the container to the temporarily placed position and a contact surface that is adjacent to the guide surface and that forms one of the contact sections, and wherein the container mounting portion has another contact surface disposed adjacent to the intersecting surface, and the other contact surface is, in the state in which the container is mounted to the container mounting portion, in contact with the contact surface and forms, together with the contact surface, one of the contact sections.

11. A container mounting structure comprising:
a container that extends in one direction and that contains powder; and

a container mounting portion to which the container is mounted by rotating the container disposed at a temporarily placed position in a circumferential direction of the container;

wherein, in a state in which the container is mounted to the container mounting portion, the container mounting structure has contact sections where the container is in contact with the container mounting portion in a radial direction of the container, and each of the contact sections is disposed at a corresponding one of at least three different positions in the circumferential direction, and

wherein the container is in contact with the container mounting portion from inside in the radial direction at one subset of the contact sections and from outside in the radial direction at another subset of the contact sections,

wherein the container includes a container body having an opening in the circumferential direction through which the powder contained in the container is discharged to outside of the container.
